(57) **CLAIM**

The ornamental design for a cosmetic LED mask as shown and described.

DESCRIPTION

1.1 is a front and right side perspective view of a cosmetic LED mask according to my new design;

1.2 is a rear and left side perspective view thereof;

1.3 is a front elevational view thereof;

1.4 is a rear elevational view thereof;

1.5 is a left side elevational view thereof;

1.6 is a right side elevational view thereof;

1.7 is a top plan view thereof; and,

1.8 is a bottom plan view thereof.

In the drawings, the equal-length broken lines depict portions of the cosmetic LED mask that form no part of the claimed design.

1 Claim, 8 Drawing Sheets
